(57) **CLAIM**

The ornamental design for an automobile headliner, as shown and described.

DESCRIPTION

FIG. 1 is a left perspective view of an automobile headliner showing our new design;

FIG. 2 is a right perspective view thereof;

FIG. 3 is a front perspective view thereof; and,

FIG. 4 is a bottom plan view thereof.

In the drawings, the broken lines depict an automobile interior and form no part of the claimed design.
